2,496,418

MACHINE FOR ROLLING AND SETTING
LEATHERCharles R. Sims, Cincinnati, Ohio, assignor to The
American Oak Leather Company, Cincinnati,
Ohio, a corporation of Ohio

Application October 24, 1947, Serial No. 781,934

4 Claims. (Cl. 69—45)

1

My invention relates to machines for rolling and setting leather and particularly to improved spring board operating mechanism for such machines.

For many years the rolling and setting of leather has been carried out by a manually controlled machine in which the operator holds the edges of a leather piece to be rolled and set on a table which is elevated by a foot treadle the movement of which is determined by the weight of the operator. The leather piece extended flat-wise on a bed plate is engaged by a ball or roller carried by a rocking beam which swings back and forth in a predetermined area over the table and plate. With each sweep of the arc of the rocking beam, the roller or ball engages the upper surface of the leather piece and rolls across it thereby giving it a desired finish and set.

Tension is provided by a spring board which forms part of a table which is raised and lowered by means of a foot treadle. The spring board is secured loosely at its ends and the flexing of the middle of the board causes a limited up and down movement. The operator pushes down and releases the foot treadle and the bed plate carried by the spring board is elevated, while the roller is carried back and forth across by the oscillations of the rocking beam. When the roller is at one end of the stroke and is at rest for a brief instant, the operator moves or slightly rotates the piece on a pivot represented by a point at which the roller is at rest. Then the roller or ball traverses a different area of the piece on its return sweep. When the roller is at the other end of its stroke, the operator moves or slightly rotates the piece again on a pivot represented by the rest point at that end of the stroke of the roller. Thus by an alternate twisting of the piece first with one hand and then the other, the entire area of the piece is finally traversed and rolled by the roller.

The operation is one requiring not only great manual dexterity on the part of the operator, but a constant strain due to pressing down on the foot treadle to secure such tension as can be accomplished in this way by thus elevating the table carrying the bed plate and the leather piece into contact with the ball as it oscillates back and forth.

The necessity for rolling and setting leather is that the previous treatments of the hide and the piece into which it is cut, leaves the leather with the grain side covered with little cavities or hair follicles. Further the fat of the animal from which the hide comes causes what are called fat

2

wrinkles. The purpose of rolling and setting the leather is to close up the follicles, smooth out the wrinkles and contract the hide so that it will have a substantially uniform firmness. This effect cannot be accomplished by a straight downward pressure applied to different areas of the leather piece, and it is only when the compression is accomplished by a rolling movement, that the various objects are accomplished.

10 Prior to my invention, the mechanisms in use which depend primarily on the skill of the operator in manually moving the leather piece over the table, and in applying his weight to the foot treadle to elevate the table, require exhaustive labor, and there is constant danger that the piece will slip and that the hand of the operator will be crushed under the ball. Further with a foot treadle determining the position of the spring board and bed plate, a sudden doubling over of 15 an end of a leather piece causes a violent upward thrust of the foot treadle which is liable to cause injury to the operator in various ways.

It is the object of my invention to pneumatically control the elevation of the table at predetermined pressures with a quick air release to greatly reduce the labor involved and to more perfectly roll and set the leather. This is because the operator, since no throwing of his weight on a foot treadle is required to cause good rolling, can concentrate more effectively on the movement of the leather on the table. The quick release enables the operator to avoid crushing the edges of the leather piece. The ball must roll across the edge under pressure but return not under pressure and 35 the arrangement proposed overcomes this difficulty more quickly than an operator can accomplish it with a foot treadle release.

It is an object of my invention further not only to facilitate the operation of the machine, but to 40 make it possible for the operator to greatly increase the amount of pressure of the ball against the upper surface of the leather. With a foot treadle the weight of the operator and the linkage determines the upward pressure which the operator can contain. With the pneumatic control and various adjustments to control the application of 45 pneumatic pressure, an easily regulatable uniform and satisfactory working pressure can be obtained irrespective of the thickness of the leather. With 50 a foot treadle varying thicknesses of leather do not receive the same rolling pressure since the pressure is dependent upon the adjustment of the machine and the thickness of the leather.

The foregoing objects and other objects to 55 which reference will be made in the ensuing dis-

closure, I accomplish by that certain combination and arrangement of parts of which I have shown a preferred embodiment.

In the drawings:

Figure 1 is a side elevation of a leather rolling and setting machine equipped with a preferred arrangement of pneumatic controls.

Figure 2 is a sectional view along the lines 2-2 in Figure 1.

Figure 3 is a perspective view showing a detail of the apparatus by means of which the operator raises and lowers the table.

Figure 4 is a diagrammatic layout showing a preferred arrangement of pneumatic valves.

Referring first to Figures 1 to 3 inclusive, a table 1 having upright supports 2, is provided with a pressure table 3, the pressure table in the illustration shown is composed of side boards 3a and a spring board 4. This center support or spring board 4 carries a contoured bronze bed plate 4a and is elevated by movement of the center of the spring board to carry the piece of leather into contact with the ball 5 on the pendulum arm 6. The arm 6 is oscillated back and forth by means of a connecting rod 7, and a crank 8 on the shaft 9, which carries a pulley 10, rotated by a belt 11. The pendulum 6 is pivoted in the bearing 12, firmly secured to the overhead support.

Referring to Figures 1 and 2, it will be obvious that the leather piece to be rolled and set is placed on the bronze bed plate 4a, the spring board 4 carrying the bed plate 4a is elevated by the upright members 57 and 58, and the ball 5 carried by the pendulum oscillates back and forth frictionally bearing against the upper surface of the leather.

In Figure 4 I have illustrated a preferred pneumatic control which consists of a pressure control valve, the casing of which is generally indicated at 13, and a foot treadle 14 which the operator depresses when he wishes to produce upward pressure on the spring board of the table.

In the diagram, 15 indicates a source of supply of compressed fluid such as compressed air, connecting as indicated at 16, with a chamber in the base of the pressure control valve. The downward movement of the treadle controls the pressure of the air which is released from the pressure tank to the relay valve.

In the pressure control valve there is a diaphragm 17 dividing the valve into two chambers 61 and 62. The diaphragm is mounted on a shaft 18 having a longitudinal passageway 63 therein, said longitudinal passageway being open at the end 64. In the lower chamber 62 of the control valve, I provide a valve arrangement consisting of two balls 21 and 23 joined together by a shaft 65. A conical coil spring 22 is based against the bottom portion of the chamber 62 and holds ball 23 against the inlet valve seat 24 and ball 21 against the open end 64 of the passageway 63, thus closing the latter. In the upper chamber 61, there is a coil spring 19 surrounding the shaft 18 and bearing against the diaphragm 17. There is also an exhaust aperture 66 in the wall of the upper chamber 61. When the treadle 14 is depressed, the cap 20 depresses the spring 19, deforms the diaphragm 17 forcing the shaft 18 together with the ball 21 downwardly against the spring 22 and unseats the ball 23 from the inlet valve seat 24, and pneumatic pressure dependent upon the degree of movement of the treadle flows from the pipe 16 up through the chamber 62 and out the delivery line 25. As soon as the air from

the pipe 16 enters the chamber 62, it not only passes out through the outlet pipe 25, but also presses upon the lower side of the diaphragm 17. If the pressure is sufficiently great and the springs 19 and 22 are correctly balanced, the pressure will elevate the diaphragm 17, and hence the shaft 18, causing the ball 23 to again seat and close off additional pressure from the pipe 16. The pressure in the line 25, will, however, be maintained.

If it is desired to decrease the pressure in the line 25 and the chamber 27 and hence in the entire system, the operator has only to let up on the treadle 14. This reduces the tension on the spring 19 and hence destroys the balance between the spring 19 and the pressure on the lower side of the diaphragm 17. The diaphragm is forced upwardly thereby uncovering the open end 64 of the passageway 63, thereby exhausting the lower chamber 62 through the passageway and an aperture in the left side thereof communicating with the upper chamber 61. The upper chamber is exhausted through the aperture 66 in the wall of the upper chamber. When the lower chamber 62 is exhausted to the point that the tension of the spring 19 again overcomes the pressure in the lower chamber, the diaphragm will be forced downwardly and the passageway 63 again closed by the ball 21.

Passing from the pressure control valve generally indicated at 13, the compressed air passes through the pipe 25 into the relay valve generally indicated at 26. There is a chamber 27 in the upper part of the valve 26 and a diaphragm 28 which, when air enters through the pipe 25, and presses down against the diaphragm, causes the diaphragm 28 to be distorted downwardly.

There is a rod 29 mounted on the diaphragm 28 and having a cone valve 30 slidably mounted thereon. The cone valve 30 is held against its seat by means of a coil spring 31 and may be opened upon the depression of the rod 29 since there is a shoulder 29a abutting the upper rim of the cone valve 30. When diaphragm 28 is depressed by the air coming through pipe 25, cone valve 30 is opened permitting compressed air to flow through the inlet port 32 and out through the exhaust port 33. If the pressure in either of these lines becomes sufficiently great to overcome the pressure in chamber 27, the diaphragm 28 will move upwardly closing the cone valve 30 and upon continued movement will lift a disc 34 mounted under the diaphragm 28 to an extent where the exhaust or relief port 35 is opened. The disc 34 normally seals the relief port at 35.

Pressure from the outlet port 33 passes through pipe 36 where it is divided and flows through the pipes 37 and 38 to quick release valves 39 and 40.

The quick release valves 39 and 40 have flexible pistons 41 and 42, the outer periphery of which are tensioned against the seats 39a and 40a by springs 43 and 44. A projection or plug 41a and 42a seat against the opening of exhaust apertures 67 and 68.

When the air pressure comes through the pipes 37 and 38, the outer periphery of the flexible pistons 41 and 42 is deformed downwardly permitting the compressed air to pass through ports 42 and 46 to the diaphragm valves or pressure chambers 47 and 48. If the pressure in the pipes to the diaphragm chambers 47 and 48 becomes relatively sufficiently great, the flexible pistons 41 and 42 are deformed upwardly unseating the plug portions 41a and 42a, and exhausting the line through the exhaust apertures 67 and 68.

With this arrangement, sudden pressure ex-

erted on the uprights 51 and 52 creates sufficient pressure in the lines to the chambers 47 and 48 to deform the pistons 41 and 42 sufficiently to exhaust this pressure through the exhaust ports 67 and 68. This permits a quick release without the air having to back up through the entire system and is of great importance as it permits the operator to relieve the pressure of the ball 5 during the short interval between the time the ball moves out over the edge of the leather piece and the time it returns. Going out, the ball is pressed down on the leather. Coming back, if the ball was under pressure the edge of the leather piece will be struck, and if there is no provision for a quick release of pressure, the ball is likely to throw the whole piece being treated out of the machine.

In the pressure chambers there are diaphragms 49, 50, mounted on rods 51, 52, which carry swivel yokes 53, 54.

Compressed air enters through the ports 55, 56, and presses up against the diaphragms 49, 50, thereby elevating the rods 51, 52 and the yoke members 53, 54.

Referring to Figure 3, it will be observed that the upright members 57, 58 which carry the ends of the spring board 4 are coupled to levers 59, 60, so that elevation of the left hand ends of the levers as illustrated in Figure 3, will cause the uprights 57, 58 to be raised thereby bringing the piece of leather into a condition of desired frictional engagement with the ball 5.

It should be understood that controlling the degree of pressure as is done by my preferred control system, the pressure produced by elevating the leather piece into contact with the ball is substantially independent of the thickness of the leather piece which results in much more uniform rolling and setting than has heretofore been possible.

The possibility of applying a desired pressure to raise and lower the spring board carrying the work into contact with the roller or ball during its oscillation, is controlled to such a nicety that after the operator becomes familiar with the machine practically no energy is required at all to control the raising and lowering of the table.

Having thus described my invention, what I claim as new and desire to secure by Letters Patent is:

1. In a machine for rolling and setting leather in combination with a roller rotatable on a horizontal axis and mechanical means for oscillating said rotatable roller in an arcuate concave path, an arcuate plate for supporting a leather piece in the arcuate path of movement of the roller and pneumatic means for elevating said arcuate plate

to produce a controlled degree of pressure between said roller in its oscillating path and a piece of leather supported on said plate.

2. In a machine for rolling and setting leather in combination with a roller rotatable on a horizontal axis and mechanical means for oscillating said rotatable roller in an arcuate concave path, an arcuate plate for supporting a leather piece in the arcuate path of movement of the roller and pneumatic means for elevating said arcuate plate to produce a controlled degree of pressure between said roller in its oscillating path and a piece of leather supported on said plate, said means comprising a treadle operated pressure

15 control valve, a relay valve the degree of pressure in which is controlled by the pressure control valve, quick release valves the degree of pressure in which is controlled by the pressure in the relay valve and pressure chambers responsive to the degree of pressure induced in the quick release valves.

3. In a machine for rolling and setting leather in combination with a roller rotatable on a horizontal axis and mechanical means for oscillating

25 said rotatable roller in an arcuate concave path, an arcuate plate for supporting a leather piece in the arcuate path of movement of the roller and pneumatic means for elevating said arcuate plate to produce a controlled degree of pressure be-

30 tween said roller in its oscillating path and a piece of leather supported on said plate, said means comprising a treadle operated pressure control valve, a supply of pneumatic compressed fluid and interconnecting means by which the

35 treadle operated pressure control valve controls the pressure of the compressed fluid released from said supply for elevating said arcuate plate a distance because of which uniform rolling pressure will be effected irrespective of variations in the

40 thickness of the leather piece.

4. In a machine for rolling and setting leather in combination with a roller rotatable on a horizontal axis and mechanical means for oscillating

45 said rotatable roller in an arcuate concave path, an arcuate plate for supporting a leather piece in the arcuate path of movement of the roller and pneumatic means for elevating said arcuate plate to produce a controlled degree of pressure be-

50 tween said roller in its oscillating path and a piece of leather supported on said plate, said means effective to roll leather pieces at a predetermined pressure irrespective of the thickness of the leather piece.
